TEXTILE FIBER CONVERTING APPARATUS

Donald G. C. Hare, Clemson, S. C., assignor to
Deering Milliken Research Trust, New York,
N. Y., a nonprofit trust of New York

Application July 22, 1947, Serial No. 762,555

3 Claims. (Cl. 19—131)

1

The present invention relates to draft spinning machines used in the conversion of textile filaments into yarn or roving and comprises improved means for eliminating or reducing the licking of fibers onto the front or draft rolls of such machines. The invention includes also means particularly adapted for use in direct tow-to-yarn spinning machines operative both to reduce or eliminate such licking of fibers on the draft rolls and otherwise to improve the uniformity of the yarn produced by the machine.

During the drafting operation, when a fiber licks on to the draft rolls, it tends to drag with it other fibers from the strand. The resulting yarn or roving is thereby weakened and breakage is apt to occur. Even if the yarn does not actually break, its quality may be so seriously impaired as to render it unfit for its intended purpose.

The conventional clearer or scavenger rolls provided in many draft spinning mechanisms are primarily intended to prevent excessive build up of fibers on the draft rolls after the yarn has broken and while an end is being pieced up, as during such period drafting continues but the emitted fibers are not being spun. Such clearer or scavenger rolls are useful in that they tend to avoid shut down of the entire machine, which may comprise hundreds of spinning units, each time the yarn to one spindle breaks, but do not appreciably prevent the licking of fibers on the rolls, ones of the prime causes for yarn breakage.

In accordance with the invention excessive yarn breakage in a spinning mechanism is avoided by the provision of an endless belt which travels for a distance along with the emitted fibers and at the same linear speed, and then departs abruptly from their path. Preferably two such belts are provided on opposite sides of the yarn and preferably also, when yarn is being spun directly from tow, such belts extend up into the ratch and serve during such portion of their travel, to smooth and guide the filament ends in their travel to the nips of the draft rolls.

For a better understanding of the invention, reference may be had to the accompanying drawings of which:

Fig. 1 is a side view of a draft spinning mechanism, equipped with moving belts arranged for elimination of licking of fibers on the draft rolls in accordance with the invention, and

Fig. 2 is a diagrammatic side view of a direct tow-to-yarn spinning machine showing belts arranged to serve the dual purpose of elimination of licking and guidance of filaments in the ratch. 55

2

In Fig. 1, a yarn spinning mechanism is indicated diagrammatically as including a pair of feed rolls 2 and 4, a pair of draft rolls 6 and 8 and a conventional ring spinner 10. In accordance with the invention, an idler roll 12, of a diameter substantially less than that of the draft rolls and of an axial length equal to that of the draft rolls, is rotatably supported beneath and in advance of the draft roll 6 and an endless belt 14, substantially the width of the rolls is passed around the rolls 6 and 12 so as to move at the peripheral speed of the draft rolls. In Fig. 1, a second similar idler roll 13 is similarly supported beneath and in advance of draft roll 8, and an endless belt 15 passes around such second idler roll and the draft roll 8. The belts 14 and 15, as above indicated, travel at the peripheral speed of the draft rolls and diverge through a relatively small angle as they approach the idler rolls 12 and 13. The belts 14 and 15 and emitted fiber strand 16 thus travel at the same speed between the draft rolls and the idler rolls 12 and 13. Because of the relatively small diameter of the rolls 12 and 13, the belts 14 and 15 have an abrupt change of direction as they pass around these rolls and leave the vicinity of the fiber strand. This abrupt change of direction of the moving walls or belts has been found to act as a detergent to fiber licking with the result that in mechanisms equipped with such moving belt or belts, yarn breakage due to licking is largely eliminated.

Although, as indicated in Fig. 1, each of the draft rolls is preferably provided with the moving belt with its abrupt change of direction relative to that of the travel of the fiber strand, substantial reduction in licking of fibers can be effected by the provision of a single such belt passing around one or the other of the draft rolls.

In Fig. 2, a direct tow-to-yarn spinner is shown and means similar to those of Fig. 1 for eliminating licking of fibers on the draft rolls are shown combined with and forming extensions of, belts or walls moving in the ratch area for improving the uniformity of the yarn. The provision of one or two walls in the ratch area moving at the peripheral speed of the draft rolls, aids in smoothing and guiding the fibers in their travel to the nips of the draft rolls, reduces wild ends in the sliver, and results in the production of more uniform yarn. As shown in Fig. 2, the means of the present invention for eliminating licking on the draft rolls may be conveniently formed as extensions of such moving walls or belts.

In Fig. 2, a direct tow-to-yarn spinning

mechanism is diagrammatically indicated as comprising the feed rolls 2a and 4a, the draft rolls, 6a, 8a and ring spinner 10a. In accordance with the invention, a pair of idler rolls 18 and 20 are positioned relatively high in the ratch, and a second pair of idler rolls 12a and 13a are positioned beneath the draft rolls 6a and 8a, respectively; the axes of both sets of idler rolls being parallel to the axes of the draft rolls. The rolls 12a and 13a, like rolls 12 and 13 of Fig. 1 are of relatively small diameter and of a length substantially equal to the length of the draft rolls. A belt 14a, which passes around idler rolls 18 and 12a is moved at the peripheral speed of the draft rolls through engagement of one or both stretches thereof with the draft roll 6a. Similarly a belt 15a, passing around rollers 20 and 13a, is driven at the same rate through contact with draft roll 8a. Thus, at any moment, the upper 10 downwardly moving reaches of belts 14a and 15a in the ratch area operate to smooth and guide the fibers in their travel to the nips of the draft rolls and the lower parts of the belts, by their abrupt change of direction upon passage around the small idler rolls 12a and 13a, serve to prevent licking of fibers on the draft rolls as explained in connection with Fig. 1.

The invention has now been described with particular reference to yarn spinning mechanisms, but obviously the invention is applicable to drafting mechanisms irrespective of whether yarn or roving is produced. The invention is also applicable to either or both stages of a two stage tow-to-yarn process, whether employed only for elimination of licking on the lower rolls or, as shown in Fig. 2, in conjunction with one or more walls moving in the ratch area. Obviously, various changes in the particular constructions shown and described could be made without departing from the spirit of the invention. For example, although the small rolls positioned in proximity to the path of travel of the fiber strand have been described as idler rolls, these rolls could be driven, if desired, as for example, in the embodiment of Fig. 2, if driving engagement between the draft rolls and belts is insufficient to prevent slip and conventional clearer rolls could be positioned, if desired, adjacent the moving walls for continuously removing therefrom such fibers as may have adhered thereto. Other modifications will occur to those skilled in the art.

The following is claimed:

1. The combination with a yarn spinning mechanism having a final pair of draft rolls of a device for eliminating licking of fibers on said draft rolls which comprises at least one endless wall moving at the peripheral speed of the draft rolls along an elongated path, a first portion of said path being substantially contiguous and 55 parallel to the fiber strand emitted by said draft rolls and a second portion of said path converging at an acute angle with said first portion in a

direction away from said draft rolls and joining said first portion at a point spaced from said draft rolls whereby a sharply angular bend is formed in said path in the region of its departure from contiguity with said strand.

2. A combination with a mechanism for spinning a strand of fibers including a pair of feed rolls, a final pair of draft rolls spaced from said feed rolls and a twist inserting device following said draft rolls of means for eliminating licking of fibers on said draft rolls which comprises a pair of rolls of diameter substantially less than that of said draft rolls spaced from and positioned between said draft rolls and said twist inserting device and a pair of endless belts, each of which passes around one of said spaced rolls and one of said draft rolls, being driven by its associated draft roll and moves along a path of substantially V-shape in the region between said spaced roll and said draft roll, diverging in the direction toward said draft roll, each spaced roll being located at the apex of its respective belt path and one leg of each belt path being proximate to the path of the strand as it passes between said draft roll and said spaced rolls.

3. The combination with a mechanism for spinning a strand of fibers including a pair of feed rolls and a final pair of draft rolls of means for eliminating licking of fibers on said draft rolls which comprises a pair of guide rolls of diameter substantially less than that of said draft rolls and between which said strand is adapted to pass, said guide rolls being disposed on the trailing side of said draft rolls with respect to the direction of strand travel, and a pair of endless belts, each belt passing about a draft roll and one of said guide rolls, and being driven by its associated draft roll at the surface speed thereof, said guide rolls being spaced from each other to provide a slight divergence of the inner opposed reaches of said belts in the direction of strand travel, each of said belts at their points of contiguous separation from said strand following a curved path the radius of which is small compared to the radius of the draft rolls so as to prevent fiber pickup on the belt surfaces.

DONALD G. C. HARE.
